HOSE CLAMP

Harold Gass, New York, N. Y.

Application August 29, 1941, Serial No. 408,724

3 Claims. (Cl. 24—19)

This invention is a hose clamp and the objects, and functional and structural features thereof will be apparent from the following detailed description taken with accompanying drawing wherein:

Fig. 1 is a vertical side elevational view of the hose clamp according to the invention, shown partly in section.

Fig. 2 is a sectional view on the line 2—2 of Fig. 1, and

Fig. 3 is a perspective view of the clamping bracket.

According to the invention, the hose clamp 10 comprises a relatively thin metal strap 11 preferably of non-resilient but deformable and flexible stock. This strap is substantially annular and includes an inner arcuate end 12 provided with reinforcing ribs 13.

Supporting means in the form of a lug generally designated 14 is bent from the body of the strap providing a plurality of closely positioned walls 15 having horizontally aligned perforations 16 for the reception of the unthreaded portion of the threaded shank 17 of a bolt which embodies a slotted head 17'.

The other end 18 of the strap is provided with spaced perforations 19 selectively and removably receiving the free end of the threaded portion 20 of shank 17, the latter being also received in the threaded opening 21 of the upstanding wall or leg 22 of the bracket broadly denoted 23.

This bracket has a downwardly and outwardly inclined leg 24 provided with the transversely arranged opening 25 adapted to receive end 18 of the strap as illustrated.

With the bolt inserted in lug 14 and in the upstanding wall 22 and threaded in one of the openings 19, the bore of the latter prevents slackening of the strap even though the latter is encompassing a pipe line or the like not illustrated.

However the inner and outer ends 12 and 18 of the strap may be adjusted towards or away from each other depending upon the rotation of the bolt. Thus the strap may be desirably and adjustably held in a clamping relation about a pipe it encompasses. If in a clamping relation, the apex or corner 26 defined by the inclined face 27 of opening or gap 25 and the lower or outer face 28 of the lower inclined leg 24 constitute means for urging the portion 29 of the outer end 18 towards the inner end 12 of the strap, hence precluding longitudinal slippage between the inner and outer ends of the strap. More specifically, the superimposed portions 30 and 31 of the inner and outer ends 18 and 19 are held in an

abutting and clamped relation to prevent accidental slippage after the strap has been adjusted in which event outer face 32 of the bracket bears against the outer end of the strap as shown.

5 In instances where it is desired to remove the clamping relation, the bolt is adjustably rotated until it leaves the receiving opening 19 after which the outer end 18 of the strap may be desirably adjusted to permit the strap to accommodate another size of pipe.

10 Various changes may be made in details of construction and arrangement of parts without departing from the spirit of the invention or sacrificing any of the advantages thereof inherent therein.

I claim:

1. In a hose clamp, an annular strap including perforated supporting means, said strap having an inner end and an outer end movable towards or away from each other, said outer end including a plurality of spaced openings, a threaded bolt removably sustained by said supporting means, and a bracket having an upper upstanding leg and a lower leg inclined downwardly and outwardly in respect to said upstanding leg, the latter having means to adjustably receive the threaded shank of said bolt whereby the latter enters one of said openings to prevent slackening of said strap, said lower leg including a gap for receiving said outer end and having a corner portion bounding said gap, said corner portion on rotation of said shank in one direction cooperating with said outer end to urge the latter tightly towards said inner end to prevent longitudinal slippage of said ends in opposite directions.

2. In a hose clamp, an annular strap including upstanding perforated supporting means, said strap having an inner end and an outer end movable towards or away from each other, said outer end including a plurality of spaced openings, a threaded bolt removably sustained by said supporting means above said ends, and a removable bracket having an upper upstanding leg and a lower leg inclined downwardly and outwardly in respect to said upstanding leg, the latter having means to receive the threaded shank of said bolt whereby the latter enters one of said openings to prevent slackening of said strap, said lower leg including a gap for removably receiving said outer end and having a lower corner portion bounding said gap, said corner portion on rotation of said shank in one direction cooperating with said outer end to urge the latter tightly towards and against said inner end to prevent longitudinal slippage of said ends in opposite directions.

3. In a hose clamp, an annular strap including perforated supporting means, said strap having an inner end and an outer end movable towards or away from each other, said outer end including a plurality of spaced openings, a threaded bolt removably sustained by said supporting means above said ends, and a bracket having an upper upstanding leg and a lower leg inclined downwardly and outwardly in respect to said upstanding leg, the latter having a threaded opening to receive the threaded shank of said bolt whereby the latter enters one of said openings of said outer end to prevent slackening of said strap, said lower

leg including a gap having an inclined face constituting one wall of said gap, said lower leg having a bottom face disposed downwardly and outwardly relative to said inclined face and defining therewith a corner portion in part bounding said gap longitudinally thereof, said corner portion only of said lower inclined leg on rotation of said shank in one direction cooperating with said outer end to urge the latter tightly towards and against said inner end to prevent longitudinal slippage of said ends in opposite directions.

HAROLD GASS.
